MECHANISM FOR ASSEMBLING MATCH
PACKETS AND THE LIKE

Hugo Brown and Wilmer C. Nicodemus, Barber-ton, Ohio, assignors to The Diamond Match Company, New York, N. Y., a corporation of Delaware

Application October 9, 1937, Serial No. 168,145

11 Claims. (Cl. 226—4)

This invention relates to mechanism for assembling match packets and the like, and especially book matches of the type wherein each book comprises one or more cards of matches enclosed in a flexible cover having a long front flap which when closed is adapted to be tucked under the free edge of a short front retaining fold to which and the back of the cover are fastened the base or bases of the match card or cards. The mechanism herein illustrated as an embodiment of our invention has been designed for use more especially in connection with a continuous match booking machine from which the complete match books are delivered flatwise in succeeding pairs, all in similar endwise and face arrangement, that is, the larger or headed ends of the matches point in one direction and the folded faces of the books are upward, as, for example, in United States Patent No. 1,042,472, dated October 29, 1912.

The principal object of our invention is to provide mechanism of simple and efficient construction and operation which is arranged and adapted to receive the match books pair by pair as they are discharged from the booking machine, and which mechanism thereupon spaces the books of the succeeding pairs in two paths or rows, moves them to upright position, and tilts the books of each pair toward each other in such a manner that the books are assembled in alternation in a single path or row wherein adjacent books are in reversed end relation and the smooth back of each book is in contact with the folded front of the adjacent book. Such disposition of the books obviates any liability of the interlocking of the opposing folds of adjacent books (as where the folded fronts of the books are in contact) during the removal of a book from a container in which they may be subsequently stacked, as, for example, the supply hopper of a machine for vending book matches.

With this object in view (and others) our invention comprises novel features of construction and combinations of parts, which in a preferred form will be hereinafter described, the scope of the invention then being expressed in the appended claims.

In the drawings—

Figure 1 is a side elevation of a portion of the delivery end of a match booking machine equipped with book assembling mechanism embodying the principle of our invention.

Fig. 2 is a plan of the said mechanism.

Fig. 3 is a longitudinal vertical section of the mechanism, as on the line 3—3 of Fig. 2, but

showing the apparatus as in operation and the match books in their progressive relative positions.

Figs. 4, 5, 6 and 7 are partial sectional views of a book assembling wheel and the stationary book tilting cams in lateral relation thereto, showing a pair of books in the successive relative positions which they are caused to assume during the travel of the wheel.

Fig. 8 is a partial perspective view of a channeled guide structure in which the books are directly delivered by the booking machine, showing book feeding fingers for successive pairs of books.

Fig. 9 is a similar view of a cover for the said guide structure.

Fig. 10 is a transverse vertical section through the guide structure, as on the line 10—10 of Fig. 2.

Fig. 11 is a perspective view of the take-off trough, and adjuncts.

Fig. 12 is a transverse section through the trough, as on the line 12—12 of Fig. 11.

Fig. 13 is a general plan of driving connections between the booking machine and the assembling mechanism.

Referring to the drawings, 15 designates the usual intermittently rotatable flap folding wheel of a typical match booking machine, from which wheel the match books, in pairs, are delivered horizontally in similar endwise and face arrangement upon resilient supporting plates 16 by the action of a reciprocating ejector frame 17, the larger or headed ends of the matches leading and the folded faces of the covers being upwards. The plates 16 are secured at their inner ends to a base member 18 which is supported upon a bed 19 having parallel channels into which the books are ejected. The free ends of the plates overhang a stationary tucker block and are formed with spaced openings 20 through which extend resilient pads 21 of rubber or the like, which are secured to the block. These pads underlie two tucker members 22 which are carried by reciprocating arms 23 and are actuated thereby to insert the free ends of the cover flaps (a) of each successive pair of books (B) under the stapled short folds (c) of the covers at the narrow ends of the respective books. Each pair of closed books are pushed from the tucker block by the next succeeding pair of books in their passage to and upon the block.

In accordance with our invention in its preferred embodiment one of the completed books of each pair is moved rearwardly in a horizontal path while the companion book is directed in an adjacent rearwardly and downwardly inclined

path to a lower level, such paths being efficiently provided by a guide structure 24 which is supported at its respective ends by the bed 19 and also by suitable brackets 25 which are bolted to 5 an adjacent supporting frame 26. The structure 24 provides horizontal and inclined channels 27 and 28, respectively, in which the books are flatwise deposited in succeeding pairs as they leave the tucker block; it being noted that the receiving ends of the channels underlie the tucker block.

Each succeeding pair of books are positively advanced along the respective channels to a carrier element and therein inserted at the respective levels, which carrier element in its preferred form comprises a continuously rotatable circumferentially pocketed assembling wheel 29 fast on a transverse shaft 290 which is journaled in bearings on the frame 26, as will presently appear. 10 The guide structure 24 in the form illustrated embodies a horizontal floor 30 and a downwardly and rearwardly inclined floor 31 adjacent thereto. Between and longitudinally of the two floors is a wall 32 which rises from the inclined floor and 15 above the horizontal floor and has a rearward extension 33 which terminates in close relation to the wheel 29. At the outer portions of the respective floors and in spaced parallel relation to the wall 32 are side walls 34 and 35 which extend 20 beyond the rearward end of the structure and terminate in lateral proximity to the circumferential path of the pocketed wheel. The space between the walls 32 and 34 is such as to form in conjunction with the inclined floor 31 the channel 28 for the free passage of a book to the wheel 29. Secured to the horizontal floor 30, adjacent 25 and parallel to the upper portion of the wall 32, is an angle bar 36 having also a rearward extension 37 which terminates in close relation to the wheel 29. The bar 36 together with the wall 35 and the horizontal floor 30 constitute the channel 27 for the passage of a book to the pocketed wheel at a level above that of the 30 companion book.

25 The means herein shown for feeding the books of each succeeding pair along the respective channels is as follows:

The floors of the channels have therein longitudinal slots 38 through which freely extend a 35 pair of upstanding fingers 39 which reciprocate in a path between the tucker block and the pocketed wheel in a manner to engage each succeeding pair of books at the receiving end of the guide structure 24 and advance them toward the wheel. These fingers 39 are carried by the forward ends of a pair of parallel rods 40 which are 40 slidably mounted in guide bearings 41 on the respective sides of the supporting frame 26. The rearward ends of the rods are connected by a cross-bar 42 which, in turn, is pivotally connected by means of a rod 43 with a crank 44 on a shaft 45 which is driven from the main cam shaft of the booking machine, so that each succeeding pair of books, immediately upon their completion 45 at the tuckers, are advanced by the fingers 39 to the rotating pocketed wheel 29 and inserted therein at different levels. The outer open sides of the books when thus inserted project beyond the respective sides of the wheel, as seen in Fig. 4.

50 In the present instance the shaft 45 is equipped at one end with a pinion 46 which is driven from a gear 47 on the main cam shaft 48 of the booking machine, through a corresponding idler gear 49, the ratio of the gearing between the shafts being 55 two to one. (See Fig. 13.)

The guide structure 24 is provided with a cap plate 50, which is detachably supported on the outer walls of the channels, as by dowels, so that the cap can be readily removed and access had to the channels in case any books therein should become disarranged. On the underside of the cap are secured two pairs of longitudinally extending beveled projections 51 whereof one pair depend in the inclined channel 28 and the other pair depend in the horizontal channels 27, the 1 lower or acting faces of the respective pairs being spaced from and being formed to extend parallel or substantially so with the floors of the respective channels. Hence as the books in their travel along the channels to the pocketed wheel pass 1 under the opposing projections such books are slightly retarded by their facial contact with the projections, thus obviating any liability of the books being thrown forward into the wheel before the proper pockets are in receptive position for 20 the books.

The assembling wheel 29 in the form illustrated has throughout its periphery a series of equally spaced partition elements 52, each of which is inclined in respect to a radial line intersecting 25 the base of the element, thus providing outwardly diverging spaces or pockets whereof adjacent pairs are advanced progressively to the planes of the discharging ends of the respective channels 27, 28 and in timed relation to the feeding fingers 39.

In the present instance the wheel 29 is suitably geared with and driven from the main cam shaft 48 of the booking machine; that is to say, one end of the shaft 290 of the wheel has fast thereon 335 a large sprocket 53 which is connected by means of a chain 54 with a smaller sprocket 55 loose on the shaft 45 previously referred to. The hub of the sprocket 55 also carries a larger sprocket 56 which is connected by a chain 57 with a smaller 40 sprocket 58 on the hub of the idler gear 49, the ratio of the sprockets of each pair being one to 45 two.

Each partition element 52 extends from side to side of the wheel and is preferably composed 45 of three spaced blade sections, to wit, wide side sections 59 which travel in close relation to the floors of the respective channels 27 and 28, and an intermediate narrow section 60 which travels 50 in close relation to the space between the channels. Hence when the peripheral series of 55 sectional blades are assembled on the wheel there are afforded in the mid-section of the wheel a pair of circumferential spaces 61 for the reception of the rearwardly-extending portions 33 and 37 of the inner wall 32 and the angle bar 36 55 of the guide structure 24, respectively, during the rotation of the wheel. The spaces between adjacent blade sections communicate with parallel circumferential grooves 62 in the body of the 60 wheel, which grooves also receive the free ends of the extensions 33 and 37.

The pockets formed by and between the adjacent sectional partition elements are of sufficient size to receive and carry the books with 65 the outer sides of the books protruding laterally of the wheel, as seen in Fig. 4, yet permit the contained books to be freely tilted sidewise toward and between the mid-portions of the respective elements, as will now be explained.

Fastened on the respective sides of the frame 26 and in close relation to the ends of the wheel 29 are two stationary cam members 63, whereof each comprises an upstanding plate having a forward peripheral cam surface 64 merging with a rear- 75

ward curved surface 65 which is concentric with the axis of the wheel. The concentric surface is so disposed that it lies in lateral proximity to the rotary path of the outer edges of the partition elements as they travel from an upper vertical to a rearward horizontal position, or substantially so, while the cam surface 64 gradually curves forwardly and downwardly to a horizontal plane in proximity to the bases of the partition elements.

0 The cam surfaces thus provided lie in the paths of the laterally projecting outer portions of the leading or larger ends of each pair of books as such books are being carried upward by the wheel to vertical position, or substantially so, 15 thereby progressively tipping the books of each succeeding pair toward each other and transversely of the wheel until they pass their respective centers of gravity and drop into reverse endwise relation in their respective pockets; that 20 is to say, the books of the two rows previously in similar endwise and face arrangement are assembled in alternation in a single row wherein adjacent books are endwise reversed and the smooth back of each book faces the folded front 25 of the adjacent book.

The narrow intermediate blades 60 serve to guide the adjacent books during their opposite transverse movements in the respective pockets, and the inner faces of the respective cam plates afford efficient guards for the open ends of the 30 advancing pockets and their contents, when the endwise and facewise reversed books escape the opposing cam surfaces.

In Fig. 4 a pair of books are shown in their relative positions immediately upon their insertion 35 in two adjacent pockets of the wheel, and in Figs. 5, 6 and 7 such books are shown in their succeeding relative positions until they have been endwise and facewise reversed during the progress 40 of the wheel. In Fig. 3 the wheel is shown as containing a succession of pairs of books in the various relative positions which they are progressively caused to assume by their co-action with the respective opposing cam surfaces of the 45 members 63.

45 The books carried by the wheel 29, as they approach the vertical position at the top of the cam plate 63, pass upon a pair of fingers 66 which, projecting forwardly from the bottom of a rearwardly extending take-off trough 67, enter the circumferential blade spaces 61 and the grooves 62 of the wheel and lie immediately below the opposing lower sides of the proximate books. Consequently as the partition elements travel 50 downwardly and rearwardly in the continued rotation of the wheel, such members recede successively from the books contiguous thereto and coincidentally push the vertically arranged books face to face, in a single row, with the ends of the books alternately reversed and the back and front of adjacent books in contact with each other, along the fingers 66 and into the trough. (See Fig. 3.)

To ensure the orderly alignment laterally of the books entering the trough, the latter has secured thereto, at its receiving end, side plates 68 having forwardly projecting fingers 69 which are laterally flared, as at 70, and are curved to overlie the tops of the cam plates 63, thus embracing the 55 assembled books in such manner that the ends of the progressing books come in contact with the flared portions, or either of them, and are thereby moved endwise to a uniform row as they enter the trough. (See Figs. 2 and 3.)

70 The receiving end of the bottom of the trough,

in the space between the side plates 68, is horizontal, as at 71, and the remainder of the bottom is slightly inclined transversely, as at 72, the lower edge of such inclined portion having a longitudinally extending wall 73 at right angles 5 to the inclined plane. The horizontal portion 71 gradually merges with the inclined portion of the bottom, as at 74, and therefore the books initially advanced upon such horizontal portion progress therefrom in an orderly manner to and along 10 the inclined portion and in convenient position for their removal in determined quantities at the open side of the trough. (See Figs. 12 and 13.)

Arranged to overhang the receiving portion of the trough is a horizontal plate 75 which is rapidly movable upon and from the underlying books, thus ensuring the uniform level of the progressing books within the trough. In the present instance, the plate 75 is supported by the upwardly extending rearward member 76 of an angulated 20 arm having a forward depending portion 77 which is pivoted, as at 78, to the frame 26, the body of the arm being provided with a roll 79 which bears on a fluted or star cam 80 on the shaft 290 of its wheel 29. Consequently the arm is rapidly oscillated, thus actuating the plate 75 to effect the desired leveling action on the progressing books in the trough. (See Figs. 1, 2 and 3).

By the foregoing described mechanism embodying our invention it will be seen that the primary 30 object of the invention is efficiently attained, in that the match packets as they are rapidly discharged in succeeding pairs from the booking machine are inserted in the adjacent pockets of a continuously moving carrier, and as the packets 35 proceed with the carrier their outer corners encounter lateral cam members which progressively tilt the packets in a manner to arrange them in a single row and in reverse end and face relation, preparatory to their delivery to the take-off 40 trough.

It is to be understood that the invention is not limited to the particular exemplifying form thereof herein disclosed, as the mechanism may be modified within the principle of the invention 45 and the scope of the appended claims.

We claim:

1. In a machine for assembling packets each including a cover having a flat back and a folded front portion, means for supporting succeeding pairs of laterally spaced packets in similar endwise and face arrangement and for feeding to different levels the packets of each pair, and a carrier element having a succession of open pockets, means for actuating said carrier element to locate each succeeding pair of pockets for the reception of a pair of packets at said levels, one packet in each pocket, and means for progressively tipping toward the mid-section of the carrier the packets of each succeeding pair borne 60 by the carrier, thereby arranging the packets of adjacent pockets in alternate order in endwise reversed relation in a single row and with the flat back of each packet facing the folded front of the adjacent packet.

2. In a machine for assembling packets each including a cover having a flat back and a folded front portion, means for supporting succeeding pairs of laterally spaced packets in similar endwise and face arrangement and for feeding to 70 different levels the packets of each pair, and a carrier element having a succession of open pockets, means for actuating said carrier element to locate each succeeding pair of pockets for the reception of a pair of packets at said levels, one 75

- packet in each pocket, and stationary cams located in the path of the outer leading corners of the packets when they are received by the pockets, whereby the succeeding pairs of packets are progressively tipped toward the mid-section of the carrier and arranged in alternate order in endwise reversed relation in a single row and with the flat back of each packet facing the folded front of the adjacent packet.
5. In a machine for assembling packets each including a cover having a flat back and a folded front portion, means for supporting succeeding pairs of laterally spaced packets in similar endwise and face arrangement and for successively feeding to different levels the packets of each pair, and a carrier element comprising a wheel having a succession of peripheral open pockets, means for rotating said wheel to locate each succeeding pair of pockets for the reception of a pair of packets at said levels, one packet in each pocket, and means for progressively tipping toward the mid-section of the wheel the packets of each succeeding pair borne by the wheel, thereby arranging the packets of adjacent pockets in alternate order in endwise reversed relation in a single path and with the flat back of each packet facing the folded front of the adjacent packet.
4. In a machine for assembling packets each including a cover having a flat back and a folded front portion, means for supporting succeeding pairs of laterally spaced packets in similar endwise and face arrangement and for successively feeding to different levels the packets of each pair, and a carrier element comprising a wheel having a succession of peripheral open pockets, means for rotating said wheel to locate each succeeding pair of pockets for the reception of a pair of packets at said levels, one packet in each pocket, and stationary cams located in the paths of the leading outer corners of the packets when they are received by the pockets whereby the succeeding pairs of packets are progressively tipped toward the mid-section of the wheel and arranged in endwise reversed relation in alternate order and with the flat back of each packet facing the folded front of the adjacent packet.
5. In a machine for assembling packets each including a cover having a flat back and a folded front portion, means for supporting succeeding pairs of laterally spaced packets in similar endwise and face arrangement and for feeding to different levels the packets of each pair, a carrier element comprising a wheel having a succession of peripheral open pockets, means for rotating said wheel to locate each succeeding pair of pockets for the reception of a pair of packets at said levels, one packet in each pocket, and the flat back of each packet facing the folded front of the adjacent packet.
6. In a machine for assembling packets each including a cover having a flat back and a folded front portion, means for supporting succeeding pairs of laterally spaced packets in similar endwise and face arrangement and for successively feeding to different levels the packets of each pair, a carrier element comprising a wheel having a succession of peripheral open pockets, and means for rotating said wheel to locate each succeeding pair of pockets for the reception of a pair of packets at said levels, one packet in each pocket, and means for progressively tipping toward the mid-section of the wheel the packets of each succeeding pair borne by the wheel, thereby arranging the packets of adjacent pockets in alternate order in endwise reversed relation in a single row and with the flat back of each packet facing the folded front of the adjacent packet, and a take-off trough into which said packets are successively delivered in a single row as the wheel rotates.
7. In a machine for assembling packets each including a cover having a flat back and a folded front portion, means for supporting succeeding pairs of laterally spaced packets in similar endwise and face arrangement and for successively feeding to different levels the packets of each pair, a carrier element comprising a wheel having a succession of peripheral open pockets, means for rotating said wheel to locate each succeeding pair of pockets for the reception of a pair of packets at said levels, one packet in each pocket, and means for progressively tipping toward the mid-section of the wheel the packets borne by the wheel, thereby arranging the packets of adjacent pockets in alternate order in endwise reversed relation in a single row and with the flat back of each packet facing the folded front of the adjacent packet, and a take-off trough into which said packets thus arranged are successively delivered, said trough having at its receiving end forwardly projecting fingers upon which the packets are advanced as the wheel rotates.
8. In mechanism for assembling packets as they are discharged in pairs from a booking machine in similar endwise and face arrangement, a supporting and guiding element for the reception of each succeeding pair of packets, said element embodying a structure having two longitudinal channels leading to different delivery levels, means for feeding the packets along said channels to and beyond the said levels, a packet assembling element having a succession of equally-spaced open pockets, and means for actuating said assembling element in timed relation to the feeding means whereby each succeeding pair of packets are movable adjacent to the said delivery levels and in receptive position for a pair of packets.
9. In mechanism for assembling packets as they are discharged in pairs from a booking machine in similar endwise and face arrangement, a supporting and guiding element for the reception of each succeeding pair of packets, said element embodying a structure having two longitudinal channels leading to different delivery levels, and a cover for said channels having depending guide members for the packets in the receptive channels, means for feeding the packets along said channels to and beyond the said levels, and a packet assembling element having a succession of equally-spaced open pockets, and means for actuating said assembling element in timed relation to the feeding means whereby each succeeding pair of packets are movable adjacent to the said delivery levels and in receptive position for a pair of packets.
10. Packet assembling mechanism embodying a carrier wheel having a succession of spaced peripheral blades which provide a succession of open pockets each of a size for the free reception

of a packet on either side of the median peripheral portion of the wheel, said members constructed and arranged to afford a pair of spaced circumferential pockets between the sides of the wheel, 5 packet guiding fingers extending into the said spaces at different levels to which each succeeding pair of packets are presented, and means for progressively tilting across the mid-section of the wheel the packets of each succeeding pair borne by the wheel.

11. Packet assembling mechanism embodying a carrier wheel having a succession of spaced peripheral blades which provide a succession of pockets each of a size for the free reception of a packet on either side of the median peripheral portion of the wheel, said members constructed 15 and arranged to afford a pair of spaced circum-

ferential pockets between the sides of the wheel, and said wheel having in its body a pair of circumferential grooves with which said spaces communicate, means for feeding a pair of packets to each succeeding pair of pockets at one location, a packet when entered in one pocket being out of line with the companion packet entered in the adjacent pocket, means for tilting across the mid-section of the wheel the packets of each succeeding pair borne by the wheel, and fingers extending into the said spaces and grooves at another location, said fingers arranged to receive and support the packets as they are discharged from the wheel.

HUGO BROWN. 15
